CONTAINER HANDLING APPARATUS

Neal S. Sells, Hooperston, Ill., assignor to Food
Machinery Corporation, San Jose, Calif., a cor-
poration of Delaware

Application June 15, 1936, Serial No. 85,223

2 Claims. (Cl. 226—129)

The present invention relates to container handling apparatus and more particularly to such apparatus which is adapted for use with containers of irregular shape, such as tapered containers and the like.

Containers of irregular shape such as conical paper containers or the like are desirable for packing certain products and particularly for shipping from the manufacturer to the plant where they are to be filled because they can be shipped in nested relation. Certain difficulties are presented in handling such containers during filling and closing because they must be maintained in upright position with their larger ends uppermost. This condition is aggravated because the center of gravity of the filled container is usually substantially above the middle portion of the container and such container has only a small flat or pointed bottom on which it can be supported. Further, practically all container handling apparatus is constructed to handle cylindrical containers and the like which will remain in upright position during handling thereof.

The present invention contemplates the provision of an apparatus for handling containers of the character referred to, including adapter means for such containers which enables filling and closing in the usual manner as with cylindrical containers and the like with no reduction in speed of operation of the handling machines and with no possibility of loss of contents of any of the containers by tipping over and spilling.

It is an object of the invention, therefore, to provide an apparatus for and a method of handling containers of irregular shape such as tapered containers and the like.

Another object of the invention is to provide an adapter which enables the use of standard filling and closing machines with containers of generally tapered shape, such as conical containers.

Other objects of the invention will appear as the description progresses with reference to a preferred embodiment of the invention as illustrated in the accompanying drawing.

In the drawing:

Fig. 1 is a vertical section through a filling machine which embodies my invention. The view is taken in a plane indicated by the line 1—1 in Fig. 2.

Fig. 2 is a plan view of the machine shown in Fig. 1 with certain parts omitted and others illustrated schematically.

Fig. 3 is a vertical section through an adapter constructed in accordance with my invention with a container shown therein in dotted lines.

Fig. 4 is a plan view of the adapter shown in Fig. 3.

The invention is illustrated in connection with the type of filling machine disclosed in the patent to Holmquist, No. 1,570,015, dated January 19, 1926, as an example of the type of machine with which my invention can be employed. However, it is to be understood that the invention can be used with other types of filling machines and with various types of container closing machines and the like.

The machine includes, generally, a supply hopper and a plurality of measuring pockets associated therewith which are periodically filled from the hopper and thereafter have their contents discharged into containers carried by a feed table. Containers are supplied to the feed table by suitable container feeding means and are discharged therefrom, after being filled, by suitable container discharge means. The machine includes base 10 which is supported by suitable standards and which has central cylindrical portion 11 providing a supporting journal for central vertical drive shaft 12. Shaft 12 provides a mounting for container carrying table 13 and extends upwardly and is journaled in hub 14 of stationary bottom plate 15 for hopper 16. Hub 14 is supported in a convenient manner by base 10.

Hopper 16 comprises part of an assembly mounted for rotation with shaft 12, including a plurality of measuring pockets 18 mounted on table 13, and a plurality of valves 19 secured to pockets 18 and to hopper 16. Each pocket 18 has a piston 21 closing the bottom thereof and operated through a connecting rod 22 from cam track 23 formed on base 10. As seen in Fig. 2, bottom plate 15 of the hopper is cut away at 26 to provide an opening through which measuring pockets 18 can be filled during their movement past such cut-away portion. Valve 19 for each measuring pocket 18 has valve plunger 27 to control the open or closed condition of the valve as determined by the engagement of a roller 28 on plunger 27 with cam track 29 mounted on frame 10 and having two portions 29A and 29B around the part of its periphery corresponding to the upward or discharge stroke of piston 21. Valve plunger 27 controls communication from the associated measuring pocket 18 to a container in position to be filled (as illustrated at the right of Fig. 1) by lifting to open passage 31, and in its

lower position controls communication with hopper 16 through passage 31 and passage 32 as per 16 through passage 31 and passage 32 as illustrated at the left of Fig. 1 when no can is in position to be filled. The conditioning of valve 5 plunger 27 is determined by which of tracks 29A, 29B roller 28 engages, track 29B being a continuation of track 29 and track 29A being elevated above track 29. To rotate hopper 16, filling pockets 18 and valves 19, shaft 12 has large gear 36 secured thereon meshing with pinion 37 on transverse shaft 38 having pulley 39 for connection by suitable belt to a source of power.

The container feeding and discharge means are illustrated more or less schematically and 15 include feed disc 41, (Figs. 1 and 2) and discharge disc 42 which are driven in synchronized relation from the main drive means. Disc 41 delivers containers to pockets formed on table 13 by spaced apart vertical wings 43 (Fig. 1).

20 To enable the handling of conical and the like shape containers which taper from a small closed end to a larger open end, an adapter is provided having means to receive and support such container while it is being handled so that 25 the adapter cooperates with the parts of the apparatus in the usual fashion of a cylindrical can or the like. Preferably, the adapter is constructed with a cylindrical exterior shape for cooperation with the handling apparatus and a 30 tapered interior shape for cooperation with the tapered container. In the illustrated embodiment, adapter 51 (Figs. 3 and 4) comprises a casting of cylindrical shape and having bottom wall 52 recessed at 53 to receive the bottom end 35 of conical container 57 and boss 54 formed integrally with side wall 55 around the open end of the adapter. The inner surface of boss 54 is of tapering or frusto conical contour to receive and support container 57 adjacent its upper 40 end. Boss 54 and walls 52 and 55 are joined by a plurality of vertical reinforcing flanges 56. As seen in Fig. 3, container 57 when placed in adapter 51 has its lower end securely held in recess 53 and is engaged adjacent its upper end 45 by the inner wall of boss 54.

The operation of the apparatus includes the placing of containers 57 in their respective adapters 51 which are then placed on feed disc 41 in any convenient manner. From disc 41 the 50 container holding adapters are transferred by suitable means to table 13 in concentric relation with respect to an associated valve 19 associated with a pocket 18 which is being filled in passing the cut-away portion 26 of bottom plate 15. If

an adapter is fed in registration with valve 19, guide track switch member 46 (Fig. 2) is swung inwardly to guide roll 28 into upper track 29A so that valve plunger 27 is moved upwardly to open position, connecting rod 22 and its associated roller move upwardly over cam track 23, piston 21 is forced up to discharge the contents of pocket 18 into the aligned container 57. Subsequently, the filled container and the adapter are discharged onto discharge disc 42 from which 10 they are removed by suitable means. If for some reason, a container holding adapter is not fed onto table 13, member 46 remains in displaced position and roller 28 follows lower track 29B so that as piston 21 moves upwardly, valve 15 plunger 27 is positioned to direct the contents of the pockets 18 back into hopper 16.

From the above description, it is seen that the adapter of my invention enables the use of tapered containers in handling apparatus designed for use with cylindrical cans or containers without any danger of the container being tipped over because of its irregular shape or being damaged because of its more or less fragile construction.

While I have disclosed my invention as embodied in a preferred form, it is to be understood that the invention can be embodied in other forms than that described and that I consider myself entitled to such variations and modifications thereof as are included in the scope of the claims appended hereto.

I claim:

1. An adapter for enabling handling of tapered containers in a machine constructed for use with cylindrical containers, comprising a cylindrical casing, and vertically spaced container engaging means for cooperative engagement with the side wall of a tapered container above and below the mid-point thereof to support and hold a container for movement as a unit with the casing.

2. An adapter for enabling handling of tapered containers in a machine constructed for use with cylindrical containers; comprising a cylindrical casing open at one end, a pocket 45 formed in the closed end of said casing to receive the small end of a container and to engage the side wall thereof adjacent said small end, and a tapered holding surface adjacent the open end of said casing for engaging the side wall of the 50 container above the mid-point thereof and adjacent the large end thereof.
